A. L. POWELL.
TRANSMISSION FOR ENGINES.
APPLICATION FILED DEC. 8, 1920.

1,384,341.

Patented July 12, 1921.

UNITED STATES PATENT OFFICE.

ALVAH L. POWELL, OF MILES CITY, MONTANA, ASSIGNOR TO THE A. L. POWELL POWER CO., OF MILES CITY, MONTANA, A CORPORATION.

TRANSMISSION FOR ENGINES.

1,384,341.

Specification of Letters Patent. Patented July 12, 1921.

Application filed December 8, 1920. Serial No. 429,175.

To all whom it may concern:

Be it known that I, ALVAH L. POWELL, citizen of the United States, residing at Miles City, in the county of Custer and State 5 of Montana, have invented certain new and useful Improvements in Transmission for Engines, of which the following is a specification.

My invention relates to improvements in 10 the transmitting member of engines, by which I secure a variation in the movement of the piston with reference to that of the crank, enabling me to gain advantages in the operation of such engines that are not 15 possible with the constructions at present used. This application covers improvements over the forms given in a series of applications serially numbered 429,168, 429,170 to 429,174 inclusive, and 429,176, of 20 which this is one, bearing the same date. In the annexed drawing I show an application of my invention, in which the figure is an elevation, giving the improvement as attached to a standard gas engine.

In my prior applications I have shown 25 different means of operating the transmitting members, and in this I describe a method similar to others already given; but in the present application I provide a detail 30 of importance in operating particular forms of my invention, and it is to this improvement that I confine myself.

In the figure, a yoke, D⁴, is attached to a 35 piston A by a rod, A¹. This yoke is slotted, and engages eccentrically formed rollers A². One of these is shown in solid lines; the other, on opposite side of engine being rendered in dotted lines. The rollers described 40 are rotatably mounted on pins, B¹, B¹, on crank levers B, B, that turn on pins, B², B². The centers of these pins are eccentric to 45 each other. This variation is indicated in dotted lines. On the pins B² are also mounted segmental pinions, attached to the crank levers, and rotatable with them. These pinions engage the toothed crank rod B⁵, the latter conventionally attached to a wrist pin, on the engine crank.

It is evident that downward movement of 50 the piston A will cause the crank levers to be depressed, the segmental pinions forcing the crank rod B⁵ in a direction indicated by the arrow near the crank shaft. As the connecting rod advances its angularity with

reference to the engaging pinions will be- 55 come greater, and the space between them will vary. The eccentricity of the pinions B³, B³, will compensate for this, the segmental pinion B³ moving away from the center line of the engine as the opposite one 60 recedes. This will result in a variation in the movement of the segments in relation to each other, the motion of one being, at times, different from that of the other. The effect 65 of this variation would alter the proper functioning of the rollers in the slotted yoke if no compensating means were provided to allow for it. This is furnished by the eccentric form given them. As shown in the drawing, the eccentric roller A² will permit 70 a certain loss of movement between the motion of the yoke and that of the crank lever B, the lost motion being taken up by the partial rotation of the eccentric roller. By setting these rollers in a proper relation to 75 the eccentrically disposed segmental pinion centers, B², B², the variation in distance between the pinions and toothed crank connecting rod is compensated for at all points; that is, the segmental pinions will follow the 80 alterations of position that arise from the angularity of the movement of the connecting rod, while the eccentric rollers in the slotted yoke will govern the variation of movement of the oppositely placed crank 85 levers, permitting a certain lag in the pressure of the slotted yoke, at moments necessary to the proper functioning of the segmental pinions. The curved form of the slot in the yoke is to assist the movement of 90 the eccentric rollers.

What I believe is new and ask to have protected by Letters Patent, is—

In a differential transmission member, the combination of pins, rocking levers mounted 95 on said pins, segmental pinions eccentrically mounted on said pins and rotatable with said levers, eccentric rollers on said levers, slotted forks engaging said eccentric rollers, a yoke supporting said forks, a bar extending 100 from said yoke, a piston, means of attaching the bar to said piston, a rack, a crank connecting rod forming part of said rack, and means whereby the teeth of the before mentioned pinions mesh with said 105 rack, for the purpose hereinbefore described.

In testimony whereof I affix my signature.
ALVAH L. POWELL.
